DILUTER-DEMAND PRESSURE BREATHING
OXYGEN VALVE

Kenneth S. Scott, United States Navy

Application February 5, 1947, Serial No. 726,507

3 Claims. (Cl. 137—153)

(Granted under the act of March 3, 1883, as
amended April 30, 1928; 370 O. G. 757)

1

This invention relates to improvements in oxygen mask valves of the demand type.

An object of this invention is to provide a device which gives a valve of the demand type of oxygen delivery without appreciable negative pressure requirements.

Another object of this invention is to provide a valve that will give a varying dilution of oxygen with air at various altitudes; providing lesser amounts of oxygen and greater amounts of air at lower altitudes and conversely, greater amounts of oxygen and lesser amounts of air at higher altitudes, up to altitudes that require pure oxygen.

A further object of this invention is to provide a valve for an oxygen mask that is small, light, and compact and is primarily without spring action in order that it may be made integral with the oxygen mask or may be used as an accessory apparatus connected to a mask by tubing or the like.

Other objects and advantages of this invention will become apparent as the discussion proceeds and is considered in connection with the accompanying claims and drawing, wherein like characters of reference designate like parts throughout and wherein:

The figure in the drawing is a cross-sectional view of the valve embodied in this invention, showing the valve as an integral part of an oxygen mask.

Referring now to the drawing, wherein for the purpose of illustration is shown a preferred embodiment of this invention, and wherein like characters of reference designate like parts throughout, the numeral 3 designates the case or facepiece of a conventional oxygen mask of the type adapted for use in flying at high altitudes, having an exhaust valve or port 4. Carried by the mask 3 is a case 5 of the valve embodied in this invention held in place in the mask by lips or tongues 6. The case 5 may be of any size or configuration desired and by its walls forms a cavity or chamber 7. An inlet tube or pipe 8 is connected to an oxygen tank (not shown). A second inlet 9 communicates with the outside air and permits passage of air into the chamber 7. After the air and oxygen is mixed, exhaust thereof from the valve is provided for by means of a passage 10, which in turn communicates with the inside of the mask 3.

A tubular sleeve or standpipe 11 is rigidly affixed to and depends inwardly from the bottom wall (reading the drawing from left to right, the right side is designated as the bottom) of the

case, into the chamber 7. Communication between the standpipe 11 and the oxygen intake 8 is provided for by means of a nipple or other connection 12. The end or inside terminus of the standpipe 11 is completely closed, in any suitable manner, as by a cap 13. Disposed circumferentially between the cap 13 and the bottom of the standpipe is a plurality of apertures or holes 14. The size and spacing of the said holes 14 will depend upon the specific design of each valve, as the total area of the holes will limit the maximum volume of oxygen that enters the valve.

A tubular sliding sleeve valve 15 extends over the standpipe 11, as shown. The said sleeve valve 15 is constructed with an inside wall 16 and an outside wall 17 which form between them a chamber 18, closed at its lower terminus 19. A plurality of venturi 20 are provided, circumferentially of the valve 15, and extend through the chamber 18, as shown, and are placed substantially adjacent to and coact with the holes or apertures 14 in the standpipe 11. The inside, or upstream ends 21, of the venturi 20 are affixed to or are made integral with the inside wall 16 of the sleeve 15, the throat or low pressure portion 22 of each venturi is disposed within the chamber 18, and the outside, or downstream end 23, of each venturi is affixed to or made integral with the outside wall 17 of the sleeve 15, as shown. The throat or low pressure portion 22 of each venturi is provided with apertures 24 which communicate with the chamber 18. A movable plate 25 carries the upper end of the sleeve valve 15 and is provided with a centrally located opening 26 which forms, in itself, a valve seat and communicates with the chamber 18 of the valve 15, as shown. A spring-loaded or one-way valve 27, having a spring 28, is carried by a lip or bridge 29, provided as shown, in the chamber 18 of the sleeve valve 15. The plate 25 is carried by a resilient case or bellows 30, as shown, and the combination of the plate and bellows form a chamber 31, which communicates with the outlets 23 of the venturi 20, and likewise with the oxygen-air mixture outlet 10.

A pressure breathing aneroid 32 is provided in, but sealed from, the chamber 1, as shown, with a flexible wall such as a bellows 33 or the like, carrying a moving plate 34. A pin or stop 35, provided within the aneroid chamber proper and carried by the case 5, limits compression of the aneroid. A tube 36 terminates at one end 36a in open communication within the chamber of the aneroid 32, and the opposite end of the tube

36b terminates in the atmosphere. A valve 37, operated either manually or automatically, is provided in the tube 36, as shown. The plate 34 of the pressure breathing aneroid 32 is rigidly affixed to the plate 25 by an open bridge 38, as shown.

Within the bridge structure proper is a second air-diluting aneroid 39, carried by the plate 34 of the aneroid 32. Bellows 39a and a closure plate 40 complete the closure of the air-diluting aneroid 39. Affixed to and carried by the closure plate 40 is a tubular valve 41 which surrounds the seat opening 26 and seats on an annular seat 42 provided on the plate 25, as shown.

In operation, either high or low pressure oxygen is delivered to the standpipe 11 and when the sliding sleeve 15 is moved into a position where the upstream Venturi intakes 21 are opposite the openings 14 of the standpipe 11, oxygen passes through each venturi into the chamber 31. The low pressure across the throat of the venturi draws air from the chamber 18 through the holes or apertures 24, where it is mixed with the oxygen and thence enters the chamber 31. The air-oxygen mixture then passes into the mask 5 by means of the passage 10 where it is breathed in the conventional manner and expelled through the exhaust valve 4. Air enters the valve 5 through openings 9 and passes into the chamber 7 thence goes through the bridge structure 38, under the tubular valve 41, past the valve seat opening 26 and into the chamber 18, thence through the Venturi throat openings 24 and out the venturi as described above. There will be some leakage of oxygen taking place between the sleeve valve 15 and the standpipe 11; however, this will be in such small amounts and will vent itself into the chamber 31 where it ultimately will be used. To prevent a loading caused by any accumulation of oxygen that may occur between the sleeve and the top of the standpipe, a vent 43 is provided in the upper portion of the sleeve 15, as shown.

The normal position of the valve 15 is closed, with the venturi 20 raised above the opening 14. During inhalation, the plate 25 is pulled downwardly, because of the reduction in pressure in the mask. As this cover plate 25 moves downward, the sleeve 15 is brought down, and the venturi 20 and the holes 14 coincide. Oxygen then flows through the venturi until a positive pressure is built up within the mask and consequently within the chamber 31 which urges the plate 25 upward, this moving the venturi away from the holes 14. It is to be here noted that no pressure is developed toward opening or closing the sleeve valve 15 except by the negative or positive pressure of breathing.

The pressure breathing aneroid is designed so that at approximately 35,000 feet or at any other desired altitude, the valve 31 would be closed, thus sealing the chamber of the aneroid 32 so that the chamber expands with increasing altitude and because of the connection by the bridge 38, puts pressure on the plate 25, causing the oxygen sleeve valve to progressively remain open at increased altitudes and to remain open except when the mask pressure is above atmospheric pressure at that altitude.

The air-diluting aneroid 39 is preferably sealed at any desired pressure before assembly in the valve. The pressure at which this aneroid is sealed depends upon the specific design of each valve and the altitude at which the aneroid is intended to function; however, adjustable means

(not shown) may be provided to vary the seal pressure of the aneroid 39. As the atmospheric pressure in the chamber 7 decreases, the aneroid 39 expands and urges the plate 40 downwardly, causing the tube valve 41 to gradually close on the seat 42. With proper setting of this air-diluting aneroid 39, the valve will close at altitudes demanding pure oxygen, with less and less air admitted as the completely closed position is approached.

It is to be understood that the form of this invention, herewith shown and described, is to be taken as a preferred example of the same, and that various changes in size, shape and arrangement of parts may be resorted to without departing from the spirit of this invention, or the scope of the subjoined claims.

The invention described herein may be manufactured and used by or for the Government of the United States of America for governmental purposes without the payment of any royalties thereon or therefor.

What is claimed is:

1. A unitized pressure breathing oxygen valve comprising a housing having a chamber therein, air inlet means communicating with said chamber, a variable volumetric chamber within the first-mentioned chamber consisting of a bellows carrying a movable plate, an oxygen-inlet valve in the said variable chamber actuated by the said plate, oxygen inlet means communicating with said valve, air inlet means carried by the said plate communicating with the said oxygen-valve, oxygen-air outlet means communicating with said variable chamber, a pressure breathing aneroid in the said housing chamber coacting with the aforesaid plate, an air-diluting aneroid, and a valve carried by the said air-diluting aneroid coacting with the said air inlet means carried by the said plate.

2. A diluter demand type pressure breathing oxygen regulator comprising a housing having a chamber therein, air inlet means communicating with said chamber, a plate carried by a resilient member within the said chamber, said rigid plate and resilient member forming a variable volumetric chamber within the first-mentioned chamber, oxygen inlet means in said variable chamber having holes therein, a sliding valve member carried by the said rigid plate and in sliding engagement with the said oxygen inlet means, venturi disposed circumferentially about the said sliding valve member coacting with the holes in said oxygen inlet means, air inlet means in the said rigid plate communicating with the said sliding valve member, an aneroid carried within the chamber of said housing adapted to regulate the sensitivity of the said variable volumetric chamber, and a second aneroid carried by the first-mentioned aneroid having an air regulating means coacting with the said air inlet means in the rigid plate.

3. A diluter demand type pressure breathing oxygen regulator comprising a housing having a chamber therein, air inlet means communicating with said chamber, a tubular bellows having a movable plate carried upon one end and being affixed to the housing at the other end forming an airtight variable volumetric chamber within the first-mentioned chamber, air inlet means in said movable plate, an oxygen air outlet communicating with said variable chamber, a tubular standpipe within said variable chamber having a plurality of holes disposed circumfer-

tially, said pipe affixed at one end to the said housing and the opposite end closed, an oxygen inlet communicating with said standpipe, a tubular sliding sleeve valve having inner and outer walls forming a chamber therebetween closed at one end and communicating with the air inlet means of said plate at the opposite end slidably mounted on the said standpipe and carried by the said movable plate, a one way valve coating between the hole in said movable plate and the said chamber of the sliding sleeve, venturi disposed circumferentially about said tubular sleeve valve coating with the holes in said standpipe, apertures in the throats of the said venturi adapted to admit air from the chamber of the said sliding sleeve valve, an aneroid carried by the said housing located within the first-men-

tioned chamber, communicating means connecting the said aneroid with the atmosphere, means connecting the said aneroid with the above-mentioned end plate, a second aneroid carried by the first aneroid, and a valve carried by the said second aneroid coating with the aperture in the said plate adapted to regulate the flow of air through the said aperture.
